UNITED STATES PATENT OFFICE.

LEONARD A. HOWE, OF WAUKON, IOWA.

AWNNG.

1,246,601.

Specification of Letters Patent. Patented Nov. 13, 1917.

Application filed May 12, 1916. Serial No. 97,098.

To all whom it may concern:

Be it known that I, LEONARD A. HOWE, a citizen of the United States, and a resident of Waukon, in the county of Allamakee and State of Iowa, have invented a new and useful Improvement in Awnings, of which the following is a specification.

My invention is an improvement in awnings, and has for its object to provide a frame for supporting awnings, wherein one end of the awning is connected with the roller arranged above the window or door to be screened to wind thereon, and wherein the improved frame comprises a body to which the other end of the awning is connected, and arms extending laterally from the body and hinged to the casement of the door or window, the arms being sectional and the sections being connected by a rule joint to permit the joint to fold downward but to limit the upward movement of the joint to a position where the sections are in alinement, together with a flexible member connected with the supporting means for the roller and with the upper section of the arms for assisting in raising and lowering the frame.

In the drawings:—

Figure 1 is a perspective view of the improved awning in use and with the awning folded, and

Figs. 2, 3 and 4 are diagrammatic side views showing the position of the parts during opening movement of the awning.

In the store front of the present day where prism or other glass is used just above the awning supports for lighting the interior of the building the roller which supports the awning must of necessity be placed so low on the building that in order to have the frame of the proper height above the walk, means must be provided which will permit the end of the frame attached to the building to slide up and down to permit the front edge of the awning to fold against the roller.

The present embodiment is designed to dispense with this sliding construction which is expensive and unsightly, and wherein the slide rods because of their tendency to bind do not give satisfaction. In addition when the awning is raised or lowered these slides must be moved on the rods to complete the operation of properly spreading of the awning.

In the present embodiment of the inven-

tion the awning supporting roller 1 is arranged above a window or door, being connected with the upper cross member of the casement 2, and the said roller is journaled in brackets 3, which are secured to the casement. One end of the roller is extended, and is provided with a bevel gear 4, which meshes with a similar gear 5 on a vertical shaft 6, by means of which the roller may be turned to wind or unwind the awning strip 6 which is connected at one end to the roller to wind thereon.

The awning frame is composed of pipe sections joined together in the usual manner, and the said frame comprises a body 7 to which the other end of the awning strip is connected, and arms extending laterally from the body, each arm consisting of sections 8 and 8^a as shown. The sections of the arms are connected by a rule joint 9 which is so arranged that while the sections may move freely in one direction they cannot move in the opposite direction beyond a point where the sections are in alinement. The section 8^a of each arm is pivoted to the adjacent side member of the casement by means of a bracket 10, and the rule joint is so arranged that while the joint may move downward it may not move upward beyond the level of the bracket 10.

With the parts in the position of Fig. 1, when it is desired to lower the awning, the roller is turned to wind off the awning strip. Were no means provided upon which the sections 8 of the arms could fulcrum, the sections 8^a would merely retain the position shown in Fig. 1 when the awning were lowered and it would be necessary to raise the joint 9 after the awning was lowered. To obviate this additional labor a flexible member 11 as for instance, a chain, is arranged at each side of the awning, each chain being connected to an eye 12 on the adjacent supporting bracket of the roller.

Each chain is branched at its lower end into branches 13 and 14 of approximately the same length and these branches of each chain are connected to the section 8 of the adjacent arm by means of the clips 15 shown. The branch 13 of the chain is connected to the section of the arm near the joint 9, while the branch 14 is connected to the section farther from the joint. With this flexible connection when the awning frame is lowered as shown more particularly in Fig. 2 the sections 8 of the arms

fulcrum upon the chain 11 and its branch 13 until the sections are almost in alinement when the branch 14 comes into play. Since the connection of the branches 14 with the section 8 is farther removed from the joint than that of the branches 13 there is a greater leverage brought to bear upon the joint to lift the same and straighten the sections.

10 I claim:—

1. An awning support comprising in combination with the awning, and the roller upon which the awning winds and having means for securing the same to a fixed support, of a substantially U-shaped frame consisting of a body and arms extending laterally from the body and having means at the ends remote from the body for hinging the said arms to the fixed support to which the awning is connected, the arms being sectional and the sections of each arm being connected by a rule joint permitting the connected ends of the arms to swing downwardly and limiting them to upward movement to a position of alinement, and a flexible member for each arm connected at one

end to the supporting means for the roller and branching at the other end, the branches of each member being connected in spaced relation to the section of the adjacent arm remote from the fixed support, and in such manner that they will be tautened in succession during the opening movement of the arms, the branch remote from the body being first tautened.

2. In an awning support, supporting arms for the awning having means at one end for hinging the said arms to a fixed support, the arms being sectional and the sections of each arm being connected by a rule joint permitting the connected ends of the arms to swing downwardly, but limiting the upward movement to a position of alinement, and a flexible member for each arm connected at one end to the fixed support above the arms and having a double connection at the other end with the section of the arm remote from the fixed support, the double connection providing a shifting fulcrum upon which the arm swings during the raising and lowering thereof.

LEONARD A. HOWE.
